(57) **CLAIM**

The ornamental design for a spring-loaded camlock, as shown and described.

DESCRIPTION

FIG. 1. Is a perspective view of the spring-loaded camlock design;

FIG. 2. Is a top view thereof;

FIG. 3. Is a left side elevational view thereof, the right side view thereof being symmetrical hereto;

FIG. 4. Is a front view thereof;

FIG. 5. Is a bottom view thereof; and,

FIG. 6. Is a rear view thereof.

The broken lines shown in the above-mentioned drawings are for illustrative purposes only and are not intended to form part of the claimed design.
